UNITED STATES PATENT OFFICE.

HARRY HUNTER COLESTOCK, OF ST. PAUL, MINNESOTA.

HEAT RETAINING AND TRANSMITTING DEVICE.

1,372,643.

Specification of Letters Patent. Patented Mar. 22, 1921.

Application filed September 24, 1918. Serial No. 255,542.

To all whom it may concern:

Be it known that I, HARRY HUNTER COLESTOCK, a citizen of the United States, residing at St. Paul, in the county of Ramsey 5 and State of Minnesota, have invented a new and useful Heat Retaining and Transmitting Device.

The objects of my invention are, first to provide a foot or bed warmer adapted 10 to receive highly-heated materials and to greatly conserve the heat therein; second, to provide an adjustably attachable counterpart heat-controlling cover that limits the out-flow of heat to a given portion of the outer 15 surface of said foot or bed warmer; and, third, provides the means of regulating the same; fourth, to provide an opening especially adaptable for the reception or emitting of bulky material, and a smaller 20 opening for general use or as a convenience for a hose connection; fifth, to provide suitable insulated stoppers; sixth to provide a receptacle, as above, with an outer fitting adapted to connect with an adjustably-at- 25 tachable supplementary compartment, and thereby forming a combination suitable for use as a lunch box, limited cooker or refrigerator, the said compartment having containers adapted to be adjustably at- 30 tached therein in such manner as to (a) make practical the production of different sizes of sub-compartments and afford (b) a choice as to how said sizes may be arranged relative to temperature receiving 35 benefits, and, seventh, to provide an efficient and economical construction particularly in regard to a screw threaded stopper-seat hereinafter described.

I attain these objects by the mechanism 40 illustrated in the accompanying drawings in which—

Figure 1 is a plan view of the bottom side of temperature-receiving receptacle; Fig. 2 a vertical section of entire contrivance 45 taken on the line 2 2, Fig. 1; Fig. 3 shows detached portions of Fig. 2 independently fitted together; Fig. 4 the portion of Fig. 2 from which the parts in Fig. 3 are detached; Fig. 5 a detached portion of Fig. 2.

On Sheet 2 of drawings Fig. 6 is a portion 50 of Fig. 2; Fig. 7 a vertical section of a portion of Fig. 1 taken on the line 7 7, Fig. 1; Fig. 8 a counterpart of a portion of Fig. 6; Figs. 9, 10 and 11 respectively are repetitions of upper portion of Fig. 6 except as 55 changed to show three additional of the

several possible adjustments of containers; Fig. 12 a portion of Fig. 6 showing a variation in construction.

Similar characters refer to similar parts 60 throughout the several views, the letters referring only to the main separate parts and numerals to their sub-parts.

In the form of my invention herewith illustrated receptacle A (see Figs. 1, 2 and 65 3) is a water-tight container (preferably of sheet metal) adapted to receive highly-heated material such as water, sand, etc., and which consists of three permanent walls on its edge side as well as on its intake-face side (represented herewith as the bottom) and a single 70 wall opposite the said intake-face side. Between these plural walls is provided a suitable space for air, slackened lime, ground cork or any suitable insulating material design- 75 nated in the drawings as I.

In the case of the larger opening intended for the reception of stopper C (hereinafter described) the seat for said stopper (instead of being a separately attached flange connection) is secured by simply screw-threading the flanged neck which is formed at the juncture of the inner and outer walls of the insulated portion of the receptacle.

This receptacle is provided with a fitting 85 to frictionally engage with the corresponding fittings, respectively, of a counterpart temperature-controlling cover and a counterpart compartment (hereinafter described) in such a manner as to admit of adjustment.

The openings to this receptacle are provided with especially designed stoppers described as follows:

Stopper B (see Figs. 1, 2, 6 and 7) consists of four members, viz: a cork-sleeve 30, 95 a cork-clutch-spindle 31, a plug-cork 32 and a projecting cap 33. Cork-sleeve 30 is permanently secured in cap 33 by the cork-clutch spindle 31, within which (31) is also permanently secured plug-cork 32. When 100 stopper B is applied cap 33 projects over and covers neck 25.

Stopper C consists of four members, viz: a projecting cap 41, a counterpart 40 to the same having a screw-threaded portion 40', 105 an elastic washer 42 and an intermediate wall 43, the said projecting cap 41 having an overlap 44 that permanently secures within it the said counterpart 40 as well as elastic washer 42, said elastic washer being situated 110 in the annular groove of the said counterpart 40 outside of its threaded-entering portion

40', and thus, (when stopper C is applied) placing washer 42 at such a distance from extreme temperatures inclosed in receptacle A as to be proof against their destroying effects. The projecting cap 41 and the counterpart 40 thereof, respectively, centrally incase insulating material I.

Part 23 (see Figs. 2 and 6) designates a shim, consisting preferably of insulating fiber formed into circular shape.

Temperature-controlling cover D (see Figs. 2, 3, 5, 6 and 8) consists of a wire-rimmed, sheet metal counterpart to the single-wall side of receptacle A and has 15 corrugations as illustrated. This cover is provided with a shield 52 which may consist of rubber, cloth, rubber-cloth or any suitable slightly-insulating material. This cover is also provided with the means of 20 fitting, attaching and adjusting corresponding to those of receptacle A as well as a supplementary receptacle and storage compartment F described as follows:

This compartment F (see Figs. 2, 4 and 25 6) is an attachable counterpart to either receptacle A or temperature-controlling cover D and has fittings so as to make it adapted to be attached to the former or 30 jointly attached intermediate the former and the latter. This compartment is provided with an insulated side wall and a single-wall top (illustrated herewith as a vessel upside down) and is also provided with the means of fitting, attaching and 35 adjusting corresponding to receptacle A.

This compartment is adapted to receive containers such as vessel G and tray H (see Figs. 2, 6 and 8 to 11 inclusive) which 40 said containers are similar in construction with the exception of a difference in depth. These containers are of wire-rimmed sheet-metal construction and are frictionally-attachably fitted to one another as well as to receptacle A and the single-wall portion of 45 compartment F, and (these containers) are just loose enough to fit to the inside sidewall of said compartment F as to render them easily inserted or removed.

It should be understood that shield 52 50 may only be employed for exceptional use, for instance when a softer material than sheet metal is required to rest the feet against, however, the principle involved is at variance with my plan of heat-regulation to the 55 extent that it retards the fullest outflow of heat, and therefore said shield is not included in my claims.

The principle upon which my plan of temperature-regulation is based, may be 60 more clearly illustrated by a similitude, viz: that when the end of a metallic rod (of a given length) is brought into close contact with a heated plate some of the temperature follows from the plate along the rod to its 65 disconnected end, notwithstanding the cir-

cumstance of a colder atmosphere through which the said temperature must pass; therefore it necessarily follows that when two flat surfaces of temperature-conducting material are brought in contact a change 70 of temperature would rapidly take place.

Thus it will be seen that when the flat surfaces of receptacle A and temperature-controlling cover D are adjusted to a close contact a free outflow of heat takes place, 75 (that is, assuming a difference in temperature between the inside and the outside of receptacle A) at that portion of the outer surface of receptacle A where said contact takes place. On the other hand when the 80 contact is broken by separating the said surfaces in question, and air (a highly efficient non-conductor) fills the intermediate space, the result is an insulated wall, with insulation corresponding in amount to the 85 thickness of the air space thus produced.

Therefore, the means of controlling the outflow of heat appears in simply increasing or diminishing this space and thereby securing such degree of outflow as may be 90 desired.

While the drawings herewith illustrate my invention only in one specific form, I do not limit myself thereby to all the specific detail of construction thereof. I have, 95 however, selected such specific form as I deemed best adapted to illustrate my invention in its most complete combination as shown in Fig. 2. It should therefore be understood that the fundamental portions 100 of my invention, (viz. receptacle A and its counterpart temperature-controlling cover D) as shown in Figs. 3 and 5, are complete in themselves for uses as set forth, entirely independent of attachable storage compartment and containers, and when so used, I prefer to employ screw-thread clasp or clasps or other suitable mechanism as a means of attaching and adjustment considering such as part of my invention. Furthermore, in order to meet the requirements 105 of cheaper construction I may employ but a single opening to receptacle A and eliminate the central walls of the insulated portions of both it and the stopper as illustrated; in short, I will avail myself of all improvements in construction that experience and expediency may suggest, that is, within the limitations of my claims.

I claim:

1. A foot or bed warmer comprising a receptacle having permanently incorporated heat-insulated side and bottom walls, an exposed heat-conducting top wall projecting up and from the inner side of the said heat-insulated side wall, an intake and outlet opening and a stopper to the same.

2. A foot or bed warmer comprising a receptacle having a permanently incorporated double-walled side and bottom, heat insula-

tion between the inner and outer walls of which the said side and bottom consists; an exposed heat-conducting top wall projecting from the inner side of the said double-walled side; an intake and outlet opening comprising a flanged stopper-seat formed at the juncture of the inner and outer walls of the bottom of the said receptacle and a stopper for the same, all substantially as described.

3. A foot or bed warmer comprising an openable and closable receptacle having an insulated bottom and side wall and a heat-conducting wall opposite the said bottom wall and a temperature-controlling cover adapted to be attached in an adjustable manner to, and outwardly overlapping, the heat-conducting wall portion of the said receptacle, substantially as set forth.

4. A foot or bed warmer comprising an openable and closable receptacle having an insulated bottom and side wall and a heat-conducting wall opposite the said bottom wall, a temperature-controlling cover and means of adjustably attaching the same to the heat-conducting wall portion of the said receptacle, substantially as described.

5. A foot or bed warmer comprising a receptacle having an insulated bottom and side wall and a heat-conducting wall opposite the said bottom wall, a temperature-controlling cover adapted to be attached in an adjustable manner to, and outwardly overlapping the heat-conducting wall portion of the said receptacle, a screw-threaded flanged opening through the said bottom wall, a stopper for said opening comprising a projecting cap having a central body portion, a flange-edged outer rim, an annular groove inside said flange-edged outer rim and an inwardly-projecting overlap of the flange edge of the said outer rim and a counterpart to the said projecting cap having a central body portion, a screw-threaded portion, an annular groove corresponding to the said annular groove of the projecting cap and an elastic washer, all the said parts of the said stopper being permanently secured together, the said washer being secured in the annular groove of the said counterpart outside of the screw-threaded entering portion of the said stopper; space between the central portions of the said projecting cap and counterpart thereto and insulating material incased in said space all substantially as set forth.

6. A foot or bed warmer comprising a receptacle having an insulated bottom and side wall and a heat-conducting wall opposite the said bottom wall, a temperature-controlling cover adapted to be attached, in an adjustable manner, to the heat-conducting-wall portion of the said receptacle, a flanged intake-opening through—and pro-

jecting outwardly from—the side wall of the 65 said receptacle, a stopper to said opening consisting of a cap with an annular projection, which projection covers the neck of the said intake opening; a spindle permanently secured to and within the said cap, a cork-sleeve permanently secured on the outer surface of the spindle and a cork-plug permanently secured within the said spindle, the said spindle having flanged ends, substantially as described.

7. A device of the character described, comprising an openable and closable receptacle having insulated bottom and side wall and a heat-conducting wall opposite the said bottom wall; a temperature-controlling 80 cover adapted to be attached, in an adjustable manner to, and outwardly overlapping, the heat-conducting-wall portion of the said receptacle; a supplementary compartment also adapted to be attached in an adjustable manner to, and outwardly overlapping, the heat-conducting-wall portion of the said receptacle, the said compartment having an insulated side wall and a non-insulated top-wall and a fitting at the top portion adapted 85 to receive, in an adjustable manner, the said temperature-controlling cover, and a fitting at its bottom portion adapted to be attached, in an adjustable manner to, and outwardly overlapping, the heat-conducting-wall portion of the said receptacle; containers for the said compartment adapted 90 to be adjusted therein as well as to the heat-conducting-wall portion of the said receptacle, substantially as set forth.

8. A device of the character described comprising a receptacle having a double-walled side and bottom, between which walls is incased insulating material; a heat-conducting wall opposite the bottom wall, a flanged stopper-seat formed at the juncture of the inner and the outer walls of the bottom of the said receptacle; a stopper comprising a projecting cap having a central body portion, a flange-edged outer rim, an annular groove inside said flange-edged outer rim and an inwardly-projecting overlap of the flange edge of the said outer rim and a counterpart to the said projecting cap having a central body portion, a screw-threaded portion, an annular groove corresponding to the said annular groove of the projecting cap and an elastic washer, all the said parts of the said stopper being permanently secured together, the said washer being secured in the annular groove of the said counterpart outside of the screw-threaded entering portion of the said stopper; space between the central portions of the said projecting cap and counterpart thereto and insulating material incased in said space and a temperature-controlling cover adapted to 110 be attached in an adjustable manner to, and 115

120

125

outwardly overlapping, the heat-conducting wall portion of the said receptacle all substantially as set forth.

9. A device of the character described comprising a receptacle having a double-walled side and bottom between which walls is incased insulating material; a heat-conducting wall opposite the said bottom wall; a screw-threaded flanged intake opening 10 through the said double-walled bottom; a stopper for said opening comprising a projecting cap having a central body portion, a flange edged outer rim; an annular groove inside said flange-edged outer rim and an inwardly-projecting overlap of the flange edge of the said outer rim and a counterpart to the said projecting cap having a central body portion, a screw-threaded portion, an annular groove corresponding to the said 15 annular groove of the projecting cap and an elastic washer all the said parts of the said stopper being permanently secured together, the said washer being secured in the annular groove of the said counterpart outside of the 20 screw-threaded entering portion of the said stopper; space between the central portions of the said projecting cap and counterpart thereto and insulating material incased in said space; a flanged intake opening through 25 and projecting outwardly from, the side wall of the said receptacle; a stopper for the same comprising a cap with an annular projection, which projection covers the neck of the said intake opening; a spindle permanently secured to and within the said cap; a cork-sleeve permanently secured on the outer surface of the spindle and a cork-plug 30 permanently secured within, the said spindle having flanged ends; and a temperature-controlling cover adapted to be attached, in an adjustable manner to, and outwardly overlapping, the heat-conducting wall portion of the said receptacle all substantially as described.
- 45 10. The combination in a foot or bed warmer of an openable and closable receptacle having a double-walled side and bottom, between which walls is incased insulating material; a heat-conducting wall opposite the said bottom and a screw-threaded-

flanged stopper seat formed at the juncture of the inner and outer walls of the bottom of the said receptacle, substantially as set forth.

11. The combination in a foot or bed warmer of an openable and closable receptacle having a double-walled side and bottom, between which walls is incased insulating material; a heat conducting wall opposite the said bottom and a screw-threaded- 55 flanged stopper seat formed at the juncture of the inner and outer walls of the bottom of the said receptacle; and a temperature-controlling cover adapted to be attached, in an adjustable manner, to the heat-conducting-wall portion of the said receptacle.

12. The combination in a device of the character described of an openable and closable receptacle having a double-walled side and bottom, between which walls is incased 60 insulating material; a heat-conducting wall opposite the said bottom and a screw-threaded-flanged stopper seat formed at the juncture of the inner and outer walls of the bottom of the said receptacle; a temperature-controlling cover adapted to be attached, in an adjustable manner, to the heat-conducting-wall portion of the said receptacle- 65 70 75 80 85 90 95

In witness whereof I affix my signature in presence of two witnesses.

HARRY HUNTER COLESTOCK.
